[57] CLAIM

The ornamental design for a vehicle trailer hitch adapted bicycle carrier, as shown.

DESCRIPTION

FIG. 1 is a front-side perspective view of a vehicle trailer hitch adapted bicycle carrier showing my new design;

FIG. 2 is a front elevational view thereof;

FIG. 3 is a side elevational view thereof showing the side opposite to that shown in FIG. 1;

FIG. 4 is a rear elevational view thereof;

FIG. 5 is a top plan view thereof; and

FIG. 6 is a bottom plan view thereof.
